UNITED STATES PATENT OFFICE.

FRANK SCHILLING, OF MUNCIE, INDIANA, ASSIGNOR TO THE C. S. NORRIS & COMPANY, OF NEW YORK, N. Y.

DESIGN FOR A BOTTLE.

SPECIFICATION forming part of Design No. 30,562, dated April 18, 1899.

Application filed March 20, 1899. Serial No. 709,856. Term of patent 14 years.

To all whom it may concern:

Be it known that I, FRANK SCHILLING, a citizen of the United States, residing at Muncie, county of Delaware, and State of Indiana, have 5 invented and produced a new and original Design for Bottles, of which the following is a specification, reference being had to the accompanying drawings, forming a part thereof, and wherein like letters of reference indicate 10 corresponding parts in the several views, and in which—

Figure 1 is a perspective view of a bottle, showing my new design. Fig. 2 is a section on the line 2 2, Fig. 1, looking upward; and 15 Fig. 3 is a bottom plan view.

As shown in the drawings, the leading or material features of my design consist of a bottle A, formed octagonal in cross-section. Adjacent the upper portion of the bottle just 20 below the neck portion B is a bulge, forming

a rounded shoulder C. The neck portion of the bottle is circular in cross-section and is provided with an annular rib or shoulder D on its upper edge. Located adjacent the lower portion of the bottle is a bulge, forming a rounded shoulder E. Below this shoulder the bottle is provided with the short vertical sides F, extending to the bottom of the bottle. 25

Having thus described my invention, what 30 I claim as new, and desire to secure by Letters Patent, is—

The design for a bottle, substantially as shown and described.

In testimony whereof I have hereunto set 35 my hand in the presence of two witnesses.

FRANK SCHILLING.
